UNITED STATES PATENT OFFICE.

THOMAS WHITE, OF DETROIT, MICHIGAN.

CIGAR LIGHTER.

Application filed March 10, 1922. Serial No. 542,569.

To all whom it may concern:

Be it known that I, THOMAS WHITE, a citizen of the United States, residing at Detroit, in the county of Wayne and State 5 of Michigan, have invented certain new and useful Improvements in Cigar Lighters, of which the following is a specification.

The present invention relates to cigar lighters and has for its principal object 10 to provide an electrical device for producing intense heat almost instantly.

Another important object of the invention is to provide a novel constructed core for receiving the electrical coil which is especially adapted to be used in cigar lighters or 15 like small electrical devices of this nature.

With the above and numerous other objects in view, the invention resides in certain novel features of construction, and the 20 combination and arrangement of parts as will be hereinafter more fully described and claimed.

In the drawing:—

Figure 1 is a perspective of the cigar 25 lighter,

Figure 2 is a top plan thereof,

Figure 3 is a longitudinal vertical section taken therethrough,

Figure 4 is a horizontal transverse section taken therethrough,

Figure 5 is a detailed perspective of the core used in connection with the device,

Figure 6 is a perspective of the fiber cap for the device,

Figure 7 is a detailed perspective of the holding member for said fiber cap, and

Figure 8 is a detailed perspective of the coil connection with the electrode.

Referring to the drawing in detail it will

40 be seen that 1 designates a base which is provided with a hollow collar 2 mounted thereon and fixed thereto by means of the screws 3. A hollow threaded member 4 is received in the upper end of the collar 2 and has threaded thereon a cup-shaped member 5 which receives the cylindrical casing 6. An inverted cup-shaped member 7 is mounted on the upper end of the cylindrical casing 6 and receives the hollow holding member 8 which is provided with a threaded seat in its upper end for receiving a fiber cap 9 which has extending therethrough a sleeve 10 which terminates thereabove and within the inverted cup-shaped member 7.

45 50 55 This sleeve 10 is adapted to receive an electrode in the form of soft carbon as is shown

at 11. An insulating lining 13 is situated within the cylindrical casing 6 and is preferably formed of some such material as asbestos. A strand of spring wire 14 is connected to a contact plate 15 and is wound in a coil within the cylindrical casing 6. This coil indicated at 16 is disposed about a porcelain core 17 which consists of a panel body 18 which is substantially oblong and is provided with enlarged end pieces 19 that project slightly beyond the longitudinal sides of the body 18. An aperture 20 is provided in each of the projections so that the strand of wire 14 may be passed therethrough and the upper one is also adapted to receive the goose-neck connector 22 which is in contact with the hollow sleeve 10. The goose-neck connector and the end of the strand of wire 14 and the end of the goose-neck connector 22 are held in place by means of the set screw 23. Another strand of wire 25 suitably encased in insulation is attached to the contact plate 26 and passes through the base 1 and collar 2 and is extended along the side of the cylindrical casing 6. The terminal of this strand of wire 25 terminates in a spool handle 26' that is formed of fiber or some other suitable insulating material and supports an electrode of soft carbon 27. The spool handle 26 is adapted to be rested in the receiver 29 when the device is not in use.

50 55 60 65 70 75 80 85 90 95 The contacts 15 and 26 are placed in connection with a suitable electric circuit whereby the coil 16 may be energized upon contact or close proximity of the carbons 11 and 27 so as to produce efficient heat at their contact points for lighting a cigar or the like.

Having thus described my invention with some degree of particularity it is to be understood that the present embodiment has been shown merely by way of example and that numerous changes in form, proportion, 100 and in the minor details of construction may be resorted to without departing from the spirit of the invention as hereinafter claimed.

Having thus described my invention what 105 I claim as new is:—

1. In an apparatus of the class described, an electrode, a coil therefor, a support for housing the coil and rigidly holding the electrode, a co-operating electrode and means 110 for supporting the co-operating electrode when not in use.

2. In an apparatus of the class described, a base, a cylindrical casing mounted on the base, an insulating core in the casing, a coil wound about the core, an electrode mounted on the casing and in electrical connection with the coil, a co-operating electrode, and means for supporting the co-operating electrode when not in use.
3. In a device of the class described, a base, a cylindrical casing, a pair of cup shaped members disposed at the ends of the

cylindrical casing, the bottom member supported on the base, a pair of electrodes, and a coil housed within the casing and connected to one only of the electrodes.

15

In testimony whereof I affix my signature in presence of two witnesses.

THOMAS WHITE.
